UNITED STATES PATENT OFFICE

GEORGE M. PORTER, OF NEW YORK, N. Y.

MAGAZINE FOR PRINTERS' TYPE

Application filed August 4, 1930. Serial No. 472,838.

This invention relates to magazines used in storage and transportation of printer's type particularly when set or composed, with or without a chase, and constituting a galley 5 or tray having a cover.

Ordinary type composition requires careful handling while being moved from a composing stick to a printing press, and frequently the type matter is carried considerable distance before and after proofs have been taken, as the printing is often done in a shop remote from that in which type was set.

The weight of the type and their smooth surfaces render transportation arduous, not infrequently resulting in dropping and the ensuing mixed condition known as pieing occurs.

It furthermore frequently happens that the type matter must be held for considerable period of time between setting and printing, during which the filled galleys must be stored safely and free from dirt as possible, but in a manner readily accessible when required for use.

Frequently, after the type is set or composed and made ready, a proof is pulled and then the type must be left standing till the matter is proof-read etc., and if such type is to be kept "standing" for any length of time, it is removed from the chase and bound with a string and stored. When handled, such bound forms often become pied thus causing considerable inconvenience and damage. Obviously difficulty arises in moving such forms from place to place as when transporting them to distant print shops. Often too it is necessary to keep type "standing" to await its further use in printing another edition of the printed matter.

One of the objects of the present invention is to provide a magazine or working galley in which the composed type may be placed without the use of a chase and in such manner that proofs may be obtained without removing the type from the magazine, the type extending above the side edges of the magazine and when not in use, covered with a blanket held in place by the cover when closed.

A further feature is in the provision of a magazine for holding type when set, and by

the term "type" is included ordinary hand set type, linotype slugs, monotype composition, cuts, electrotypes, etc., all matter, in fact, for printing purposes that is "type high", the holding being effective so that the type can- 55 not pi.

Another aim is to produce a magazine adapted to be filed vertically on one of its edges in a suitable cabinet whereby each magazine may be withdrawn or replaced without 60 difficulty, the magazines being indexed and tagged in accordance with their contents.

Still other objects are to provide a safe container for type in which they are held compactly in printing position by novel securing 65 means, the type being slideable outwardly in mass formation without danger of disarrangement upon release of the cover.

A still further object is to provide a safe container for composed type in which it may 70 be conveniently and safely transported from place to place.

These important features are attained by the novel construction and arrangement of few and simple parts as hereinafter described 75 and illustrated in the annexed drawing constituting a component of this disclosure, and in which:

Fig. 1, is a perspective view of a magazine made in accordance with the invention, parts 80 being broken away to disclose the construction.

Fig. 2, is a sectional view taken on line 2—2 of Fig. 1, showing the cover in closed position.

Fig. 3, is a similar sectional view of the same but with the cover partially opened.

Fig. 4, is a fragmentary sectional view taken on line 4—4 of Fig. 1, drawn to an enlarged scale.

Fig. 5, is a partial rear elevational view of a corner of the magazine.

The device shown is of very simple character, consisting of only two main parts, respectively, body and cover, both preferably 85 being composed of sheet metal formed into the shapes indicated by die stamping.

The body or tray consists of a flat rectangular plate 10 having its side and rear edges 11—12 re-entrantly folded inwardly to pro-

duce spaces 13—14 and thence turned upward at right angles with the bottom 10 to form side and rear walls respectively 15—16, the front edge 17 being straight and level.

5 Inserted between the side walls 15 is a strip 18, its upper edge being disposed in a plane of the side walls, the height of which is slightly less than "type high" above the surface of the bottom plate 10; the strip 18 is spaced parallel to the rear wall 16 and has a flange 19 which extends into the recess 14 and is secured to the bottom 10.

10 The cover consists of a plate 20 having down turned side walls 21 extending nearly or quite to contact with the upper surfaces of the extending side elements 11 of the tray.

15 The rear wall 22 of the cover is formed into a rearwardly extending flange 23 adapted to nearly fit in the recess 14 over the strip flange 19 when the cover is closed.

20 A front wall 24 is formed on the cover and provided with a rearward turned flange 25 adapted to engage in the manner of a hook under the front marginal portion of the bottom plate 10 when the cover is closed and pressed rearwardly, as seen in Figs. 1 and 2.

25 Adjacent the walls 21 notches 26 are formed in the cover rear wall 22 to rest on the body walls 15.

30 A knob 27 is fixed in the front wall 24 of the cover for convenience in moving it relative to the body.

35 Set rigidly in one corner of the body is an angular member 28 and fixed in its face is a post 29 containing a transverse opening 30 disposed vertically with respect to the body, this post being adapted to extend through a corresponding opening in the front wall 24 of the cover, this wall also carrying a pivoted hook 31 engageable in the post opening 30, thus locking the cover to the body.

40 Also carried by the corner wall 24 is a clip 32 arranged to receive tags or like devices bearing information relative to the contents of the magazine.

45 In operation, assuming the magazine to be closed, the hook 31 is raised, permitting the cover to be drawn forwardly thus releasing the hook flange 25 from engagement under the bottom of the body, and at the same time withdrawing the cover flange 23 from the recess 14, to the limit of the strip 18, whereupon the cover is cleared of the post 29 and can be raised.

50 Type, indicated at T, may be disposed in proper formation in the tray body, and if to be transported, a cushion 33, as heavy cardboard, placed over the faces of the type and the cover applied in the manner above indicated, the operation being obviously reversed.

It will be apparent that the magazine may be used to retain the type indefinitely, permitting storage on edge and ready transportation without danger of the type moving from their adjusted position, and that the type may be caused to slide outwardly when desired without being raised from their support.

55 From the foregoing it will be seen that a simple device for this purpose has been disclosed in the preferred form of its embodiment, but it is not desired to restrict the details to the exact construction shown, it being obvious that changes, not involving the exercise of invention, may be made without conflicting with the scope of the appended claims.

Having thus described my invention, what I claim as new and desire to secure by Letters Patent is:—

55 1. A type magazine comprising a tray having walls less than type high, a cover having means interengageable with the front and rear ends of said tray, and means to positively lock the cover when so engaged.

60 2. A type magazine comprising a tray having side and end walls less than type high, recessed extensions at the junction of said walls and base plate, a cover having side walls to contact said extensions, and having a rear wall provided with a flange to removably engage in the recess of the rear wall extension, and means on the front end of the tray to retain said flange in engagement.

65 3. A type magazine comprising a tray having side and end walls of fixed height, recessed extensions at the junction of said walls and base plate, a cover having side walls to contact said extensions, and having a rear wall provided with a flange to removably engage in the recess of the rear wall extension, a transverse hook on front of said cover to engage the under side of said tray, and means to confine the cover when in operative position on the tray.

70 4. A type magazine comprising a tray and a detachable cover therefor, releasable means for securing the cover on said tray, said cover constituting means for confining set type in said tray whereby the magazine may assume any position without releasing the type.

75 5. A type magazine comprising a tray and a detachable cover therefor, releaseable means at its front and rear ends for securing the cover onto said tray and means to lock the tray and cover against relative movement.

80 6. A type magazine comprising a tray, recessed bead at its side and rear edges, walls raised from said beads, the front edge being level, a stop strip in said tray spaced parallel to the rear wall, a cover having a part engageable in the recess of the bead at the rear of said tray and a hook flange to engage the bottom of the tray at its front edge, the movement of said cover being limited by said

strip, a perforated post fixed in said tray to extend through an opening in the front wall of said cover, and a latch pivoted on said wall to engage in the perforation in said post.

5 7. A type magazine comprising a tray and a detachable cover therefor, releasable means for securing the cover on said tray, means for limiting the relative movement of said cover and tray, means to lock said cover when in operative position, and means on said cover for carrying memoranda relative to the contents of said tray.

10 8. A type magazine comprising a tray having a base plate, and side and end walls less than type high, a recessed extension at the junction of the rear end wall and base plate, and a detachable cover having a rear wall provided with a flange for removable engagement in the rear wall extension of the tray.

15 20 9. A type magazine comprising a tray having a base plate, and side and end walls less than type high, a recessed extension at the junction of the rear end wall and base plate, detachable cover having a rear wall provided with a flange for removable engagement in the rear wall extension of the tray, and means to securely retain said flange in engagement.

25 30 10. A type magazine comprising a tray and a detachable cover therefor, a recessed bead at the rear edge of said tray, a stop strip in said tray spaced from the rear wall thereof, a part on one edge of said cover releasably engageable in the recessed bead, and a hooked flange on the opposite edge of said cover to releasably engage the bottom of the tray at its front edge.

35 40 45 50 11. A type magazine comprising a tray and a detachable cover therefor, a recessed bead at the rear edge of said tray, a stop strip in said tray spaced from the rear wall thereof, a part on one edge of said cover releasably engageable in the recessed bead, a hooked flange on the opposite edge of said cover to releasably engage the bottom of the tray at its front edge, a perforated post fixed on said tray to extend through an opening in the front wall of said cover, and means on said wall to engage the post to secure the tray and cover against relative movement.

Signed at New York, in the county of New York and State of New York.

GEORGE M. PORTER.
